F. F. VALLETTE

TELEPHONE SYSTEM

Filed Dec. 1, 1922

Inventor:
Frederic F. Vallette

by W. E. Beatty, Atty

UNITED STATES PATENT OFFICE.

FREDERIC F. VALLETTE, OF BERWYN, ILLINOIS, ASSIGNOR TO WESTERN ELECTRIC COMPANY, INCORPORATED, OF NEW YORK, N. Y., A CORPORATION OF NEW YORK.

TELEPHONE SYSTEM.

Application filed December 1, 1922. Serial No. 604,200.

To all whom it may concern:

Be it known that I, FREDERIC F. VALLETTE, a citizen of the United States, residing at Berwyn, in the county of Cook, State of Illinois, have invented certain new and useful Improvements in Telephone Systems, of which the following is a full, clear, concise, and exact description.

This invention relates to telephone systems and more particularly to systems wherein connections are established without the intervention of operators.

In many of the present day business activities, and particularly in connection with the business of a broker, it is often desirous, and in many cases necessary, that one member of a firm be able to get in touch with another member of the firm substantially instantaneously, in order to advise him of the sale of stocks and the like. In such cases where time is a most important element in the successful transaction of business, a system of communication is desirable wherein the time consumed in establishing a telephonic connection by an intermediate operator is used to actual advantage by the calling party.

It is an object of this invention, therefore, to improve a system for establishing telephonic connections without the intervention of operators.

Another object of this invention is to signal the called station on a private line by automatic machine ringing under the control of the calling station.

The foregoing and other objects of this invention are obtained by the provision of a private line interconnecting two subscribers' sets and having in either end thereof a relay responsive to the removal of the receiver from the switchhook at the station on that end to operate other electromagnetic devices whereby a source of machine ringing current is automatically connected to the called line.

The invention will be readily understood from the following description, and by reference to the accompanying drawing which shows two subscribers' sets and a private line circuit interconnecting said sets.

Let it be assumed that the subscriber at station A desires to communicate with the party at station B. The subscriber at station A in removing the receiver from the switchhook establishes an energizing circuit for supervisory relay 10, which may be

traced from grounded battery, through the left-hand winding of repeating coil 11, conductor 12, winding of relay 10, lower armature and back contact of relay 13, over the subscriber's line loop including the apparatus at station A, the upper armature and back contact of relay 13, conductor 14, and thence to ground through the upper left-hand winding of repeating coil 11. Relay 10 energizes in this circuit and establishes a circuit for relay 15, extending from grounded battery through the winding of relay 15, conductor 16 and thence to ground through the armature and front contact of relay 10. Relay 15 upon energizing prevents, at its left-hand armature, the operation of relay 13 at this time. At its right-hand armature, relay 15 establishes an energizing circuit for relay 18 which may be traced from grounded battery through the winding of relay 18, conductor 19, right-hand armature and back contact of relay 20, conductor 21, conductor 32, armature and back contact of relay 22, conductor 23, armature and back contact of relay 24, conductors 26, 28 and 27 and thence to ground through the right-hand armature and the front contact of relay 15. It is to be noted that relay 22 is shunted by a portion of the circuit just traced including the armatures of relays 22 and 24 and the conductor 23. This shunt is necessary at this time in order to prevent relay 22 from operating and thereby shunting out relay 18 before the machine ringing source 17 has been connected to the called party's line. Relay 18 in operating in the circuit previously traced places ground on the tip conductor of the called line and connects at its lower armature and front contact, the machine ringing source 17 to the ring conductor of the called line. The ringing current flows from the ringing source 17 through the winding of marginal relay 24, conductor 25, lower armature and front contact of relay 18, and thence over the subscriber's line loop including the apparatus at station B, to ground at the upper armature and front contact of relay 18 to actuate the bell at station B.

Upon noting the signal, the subscriber at station B removes the receiver from the switchhook thereby bridging the line conductors and reducing the resistance of the line to such an extent as to permit the marginal relay 24 to operate. Relay 24 in operating removes the shunt provided

around relay 22, thereby permitting this relay to operate in series with relay 18 over a circuit extending from grounded battery through the winding of relay 18, conductor 19, right-hand armature and back contact of relay 20, conductor 21, conductor 32, winding of relay 22, conductors 28 and 27, and thence to ground through the armature and front contact of relay 15. Relay 22 in operating places battery on conductors 32, 21 and 19 to oppose the battery normally associated with the winding of relay 18, whereupon relay 18 deenergizes and removes the machine ringing source 17 from the ring conductor leading to station B. Relay 24 also deenergizes upon the release of relay 18. Relay 18 is made slow releasing in order that the charge caused by the effect of the ringing current on the normal capacity of the line may be dissipated before the line is thrown back on the repeating coil 11 to prevent the calling subscriber at station A from receiving the effect of the charge.

When relay 18 deenergizes a circuit is established for supervisory relay 29 which may be traced from grounded battery through the lower right-hand winding of repeating coil 11, conductor 30, winding of relay 29 back contact, and lower armature of relay 18 over the line loop of station B, the upper armature and back contact of relay 18, conductor 31, and thence to ground through the upper right-hand winding of repeating coil 11. Supervisory relay 29 energizes in the circuit just traced, and establishes a circuit for relay 20 which may be traced from grounded battery, through the winding of relay 20, conductor 33, to ground through the front contact and armature of relay 29. At its left-hand armature and front contact relay 20, on energizing, connects an additional ground to the circuit including the winding of relay 22 thereby preventing this relay from releasing before relay 20 releases. The subscribers at stations A and B are now in telephonic connection with one another and may proceed to carry on a conversation.

Upon completion of the conversation the subscriber at station A replaces the receiver on the switchhook thereby interrupting the energizing circuit for relay 10. Relay 10 releases its armature thereby interrupting the circuit for relay 15. Relay 22 is still held operated under the control of relay 20, in a circuit extending from grounded battery through the armature, front contact and winding of relay 22, conductor 28, conductor 40, and thence to ground through the armature and front contact of relay 20. The subscriber at station B upon replacing the receiver on the switchhook interrupts the energizing circuit for supervisory relay 29 which retracts its armature and opens the

circuit for relay 20. Relay 20 in retracting its left-hand armature interrupts the circuit for relay 22 which relay thereupon deenergizes returning the circuit to normal.

It is to be noted that during the ringing period, the line of the called subscriber's set is removed from the repeating coil 11, the repeating coil itself not being employed in the ringing operation.

From the foregoing description, it is obvious that either subscriber by the mere act of removing the receiver from the switchhook can automatically signal the other subscriber and be telephonically connected therewith.

What is claimed is:

1. In a telephone system, a line comprising inductively coupled sections, a substitution normally connected to each of said sections, a source of ringing current, a relay responsive to the removal of the receiver at either of said stations for disconnecting the other station from its corresponding line section and connecting said current source to said other station, a normally shunted relay common to said stations, and means responsive to the removal of the receiver at said other station for removing the shunt from said normally shunted relay whereby said first mentioned relay is restored, disconnecting said ringing current from said other station and reconnecting said other station to its corresponding line section.

2. In a telephone system, a line comprising inductively coupled sections, a substitution normally connected to each of said sections, a source of ringing current, a relay responsive to the removal of the receiver at either of said stations for disconnecting the other station from its corresponding line section and connecting said current source to said other station, a normally shunted relay common to said stations, and a marginal relay controlled from said other station for removing the shunt from said normally shunted relay whereby said first mentioned relay is restored, disconnecting said ringing current from said other station and reconnecting said other station to its corresponding line section.

3. In a telephone system, a line comprising inductively coupled sections, a substitution normally connected to each of said sections, a source of ringing current, a relay responsive to the removal of the receiver at either of said stations for disconnecting the other station from its corresponding line section and connecting said current source to said other station, a marginal relay responsive to the removal of the receiver at said other station, and means controlled by said marginal relay for reconnecting said station to its corresponding line section and removing said current source from connection therewith.

4. In a telephone system, a pair of stations, a link circuit interconnecting said stations, a source of signaling current, means controlled from either of said stations for automatically connecting said source of current to the other of said stations, a marginal relay common to said stations, and circuit connections arranged so that said marginal relay may be controlled from either of said stations to automatically disconnect said source of current in response to the answering of the called station.
5. In a telephone system, a link circuit, a subscriber's station at each end of said link circuit, a source of ringing current, means

controlled from either of said stations for connecting said source to the opposite station to signal said opposite station, means operative in response to the answering of the opposite station to automatically disconnect said source of ringing current, and a relay for each end of said link circuit for rendering the conductors of said link circuit discontinuous during the signaling interval.

In witness whereof, I hereunto subscribe my name this third day of November A. D., 1922.

FREDERIC F. VALLETTE.
